GEORGE O. WICKERS, OF LAWRENCE, AND THOMAS J. MCCLARY, OF NORTH ANDOVER, MASSACHUSETTS.

Letters Patent No. 100,575, dated March 8, 1870.

IMPROVEMENT IN LOOM-CAMS.

The Schedule referred to in these Letters Patent and making part of the same.

We, GEO. O. WICKERS, of Lawrence, and THOMAS J. MCCLARY, of North Andover, both in the county of Essex, and State of Massachusetts, have invented certain Improvements in the Construction of Cams for Working the Heddles of Looms, and for other similar purposes to which such cams may be applicable, of which the following, with the accompanying drawings, is a specification.

Nature and Objects of the Invention.

Our invention relates to the construction of the series of cams which work the heddles of looms, so that they may be readily changed when it is required to change the figure of the weaving, without being obliged to remove the cam-shaft from the loom, and consists in forming the inclined and exterior portions of the cams separate from the central cylindrical portion or hub, so that the exterior part of each (including the inclines) may be placed in any position around the hub to place it in proper relation to the other cams, and may also be removed therefrom and replaced without removing the hub or central portion from the shaft or from the loom.

In the manufactures in which fancy weaving is employed, the changing of the heddle-cams is frequently necessary, and to do this in looms as usually constructed it is necessary to take the cam shaft out of the loom, remove its cams and put on others, and then put the shaft back again and adjust it. As the looms are usually placed close to each other in a factory, this is very inconvenient, and it is in any case a very dirty and unpleasant job.

Description.

In the drawings—

Figure 1 is a side elevation of a set of four cams, as used for weaving four-leaf tweed.

Figure 2 is an end elevation of the same;

Figure 3 is a longitudinal section of the same on the line *x x* of fig. 2; and

Figure 4 is a transverse section on the line *y y* of fig. 1.

A, A, &c., are the several cams made of the usual external form, and B is the hub or quill upon which all the cams are arranged in their proper order to work the heddles, and to which they are securely attached, as is shown.

This quill may be fixed upon the shaft C, and revolve with it, or turn loosely upon the shaft and receive its rotary motion from a separate gear attached to the quill, as is shown by the dotted lines at D, in a manner similar to what is usually done in looms when a separate cam shaft for the heddles is used.

E is a flange fixed to the quill, to which the outer cam on one side is secured by a bolt, *a*, and F is a movable flange upon the opposite side of the cams, which is secured to the quill by set screws *b b*, and to the outer cam next to it by the bolt *c*.

The cams are secured to each other by the bolts *d* and the dowels and sockets *e*.

The exterior of the quill is turned truly cylindrical, and the part of the cam which embraces it is bored to fit it nicely, and the inclined surfaces of the cam are made to approach the surface of the quill tangentially, as shown, to give an easy motion to the heddles. The outer part of the cams is made of the usual form.

By this mode of construction as many cams in a set may be used as may be desired, and they may be changed by loosening the flange F and removing the bolts *a*, *c*, and *d*, when they can all be slipped off from the end of the quill and removed from the shaft with freedom. Another set of cams of any required number and order of arrangement may then be put on to the quill by a reversed operation and movable flange F brought close up to them and secured to the quill by the set screws *b*, and the cams secured to each other and to the flanges E and F by the bolts and dowels, as before described.

Thus the quill B serves as the central part of all the cams used in the set, whatever may be their number or relative position to each other.

We claim as our invention—

The combination of a series of cams, A, with the quill B and the flanges E and F, for connecting the series with the quill, substantially as described.

Executed October, 1869.

GEO. O. WICKERS.
T. J. MCCLARY.
